UNITED STATES PATENT OFFICE

102,962

DESIGN FOR A KNITTED FABRIC

David Siegel, New York, N. Y.

Application November 11, 1936, Serial No. 65,845

Term of patent 7 years

To all whom it may concern:

Be it known that I, David Siegel, a citizen of the United States of America, residing in the city, county, and State of New York, have invented a new, original, and ornamental Design for a Knitted Fabric, of which the following is a specification, reference being had to the accompanying drawing forming part thereof.

The figure is a plan view of the knitted fabric showing my invention.

The design consists of series of vertically ar-

ranged relatively wide and narrow stripes resulting from loose stitches formed of threads which are of a color contrasting with the color of the fabric, the wide stripes being formed of a plurality of loose stitches, and the narrow stripes being formed of single loose stitches.

I claim:

The ornamental design for a knitted fabric, as shown and described.

DAVID SIEGEL.
